United States Patent Office

Des. 227,625
Patented July 10, 1973

227,625

CHILD'S SEAT

George A. Le Hew, 1341 Oakwood Drive,
Anoka, Minn. 55303

Filed Nov. 5, 1971, Ser. No. 196,255

Term of patent 3½ years

Int. Cl. D6—01

U.S. Cl. D6—7

FIG. 1

FIG. 2

FIG. 1 is a top perspective view of a child's seat showing my new design; and

FIG. 2 is a bottom perspective view from the side opposite that shown in FIG. 1.

I claim:

The ornamental design for a child's seat, substantially as shown.
